GARMENT BAG CARRIER

Max Berger, 310 Lakeridge Road,
San Antonio, Tex. 78229

Filed Apr. 29, 1968, Ser. No. 11,650

Term of patent 14 years

Int. Cl. D8—03

U.S. Cl. D8—154

FIG. 1

FIG. 2

FIG. 3

FIG. 4

FIG. 5

FIG. 6

FIG. 7

FIG. 8

FIG. 9

FIG. 10

FIG. 11

FIG. 1 is a top plan view of a garment bag carrier showing my new design;

FIG. 2 is a bottom plan view thereof;

FIG. 3 is a side elevational view thereof;

FIG. 4 is an end view thereof as seen from the right of FIG. 3;

FIG. 5 is a top plan view of an embodiment of my design of FIG. 1 wherein a pocket is attached thereto;

FIG. 6 is a side elevational view of the garment bag carrier of FIG. 5;

FIG. 7 is a top plan view of another embodiment of my design of FIG. 1 wherein a loop is employed rather than a buckle-strap end;

FIG. 8 is a bottom plan view of the garment bag carrier of FIG. 7;

FIG. 9 is a side elevational view of the garment bag carrier of FIG. 7;

FIG. 10 is a top plan view of a further embodiment of my design of FIG. 1 wherein a hook is employed rather than a buckle-strap end; and

FIG. 11 is a side elevational view of the garment bag carrier of FIG. 10.

I claim:

The ornamental design for a garment bag carrier, as shown and described.
